Primary Examiner — Kevin K Rudzinski*Assistant Examiner* — Paul D Bohannon(74) *Attorney, Agent, or Firm* — Fox Rothschild LLP;
Carol Thorstad-Forsyth**CLAIM**

The ornamental design for a massage chair with kiosk display and partition, as shown and described.

DESCRIPTION

FIG. 1 is a front right perspective view of a massage chair with a kiosk display and a partition showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The stipple shading is used to indicate wood panels. The broken lines in the drawings illustrate portions of the article that form no part of the claimed design.

1 Claim, 7 Drawing Sheets(56)
